UNITED STATES PATENT OFFICE.

JOHN NARIZZANO, OF HAMPTON WICK, ENGLAND.

MACHINE FOR COVERING WIRE WITH SILK, COTTON, OR THE LIKE.

1,416,497.

Specification of Letters Patent. Patented May 16, 1922.

Application filed December 30, 1919. Serial No. 248,420.

To all whom it may concern:

Be it known that I, JOHN NARIZZANO, of Hampton Wick, in the county of Middlesex, England, a subject of the King of Italy, 5 have invented certain new and useful Improvements in or Relating to Machines for Covering Wire with Silk, Cotton, or the like, of which the following is a specification.

This invention relates to machines for 10 covering wire with silk or the like, of the type in which a series of spinner heads are provided having flyers adapted to rotate about a horizontal or substantially horizontal axis, each pair being provided with a 15 separate drive, and a series of tubular bobbin holders are disposed in front of each spinner head to hold spare bobbins, so that when one bobbin is finished a new one can be moved from the holder to the spinner head.

20 The object of the invention is to provide an improved construction adapted to facilitate the operation of machines of the kind indicated.

My improved machine comprises features 25 constituting a substantial departure from the standard construction heretofore employed, and also various known elements in combination as hereinafter described and specifically claimed.

30 Referring to the drawings filed herewith:—

Fig. 1 is a front elevation, broken away of a machine made in accordance with this invention;

35 Fig. 2 is an end elevation;

Fig. 3 is a transverse section.

On the frames *a a* of the machine are mounted a main shaft *b* and a counter shaft *c*. On the main shaft *b* are mounted fast 40 and loose pulleys *d* a toothed pinion *e* and a series of grooved pulleys *f f*. On one frame *a* is also mounted an arm *g* on which is disposed a train of change speed gear wheels *h j k* and a removable pulley *m*, the diameter of which varies according to the speed 45 at which it is desired to drive the counter-shaft *c*. The arm *g* is also fitted in such a way that it can with its gear wheels be moved radially about the centre of the shaft *b* in order to compensate for the slackening 50 of the belt *p* caused by the changing of the pulleys *m*.

On the shaft *c* are mounted a series of grooved wheels *n* and a pulley *o* adapted to 55 be driven from the pulley *m* by a belt *p*.

On the frame *a* of the machine are two

beams *r s* on which are mounted a series of pairs of spinner heads *t t* arranged one in advance of the other provided with flyers *t' t'*, and a series of hangers *v v*. On the 60 hangers *v v* are mounted grooved pulleys *w w*. A driving cord *x* passes over each pulley *f* over two pulleys *y y* on the flyers and over the pulleys *w w* so that the spinner heads on the beam *r* rotate in the opposite direction from the spinner heads on the beam *s*. 65

On the frame *a* is mounted a beam *2* on which are disposed arms *3* carrying grooved pulleys *4* and *5* and winding up bobbins *6*. 70 The bobbins *6* are each driven separately by a cord *7* passing over the grooved wheels *n* and the corresponding pulleys *4* and *5*.

The beam *s* carries a series of tubular bobbin holders *8*. On the frame *a* is a beam *z* 75 on which are mounted a series of guide pulleys *10* and bobbin holders *11*. On the frame of this machine is mounted a beam *12* carrying studs *13* each adapted to carry a spool *14* of wire to be covered. On the frame *a* is 80 mounted a small shaft *15* on which are disposed loose guide pulleys. The wire *17* is led through the spinner heads *t* and bobbin holders *8* and *11* once round the pulley *n* through the guide *18* to the bobbin *6*, the 85 guides *18* are moved from left to right and vice versa on the rod *29* which obtains its motion through the crank arrangement 30 operated by a worm gear *31* from the countershaft *c*. 90

On each stem *13* is a hollow spindle *19* carrying a pulley *20* on which is disposed a cord *21* adapted to be kept taut by a weight or spring and adapted to act as a brake on the spools *14* and prevent their overrunning. 95

The spinner heads are held in position by plates *22* adapted to clamp the spindles of the heads on to the beams *r* and *s*.

23 is a striking rod mounted in brackets 24, 24, and adapted to operate the striker 25 100 through lever *26* rocking shaft *27* and crank *28*.

The bobbins on which the covering material is wound are provided with a slit or adapted to be cut so that when empty the 105 wire can be slipped through the slit when it is desired to remove it and place a full bobbin on a spinner head.

In use a bobbin of silk is placed on each spinner head and spare bobbins are placed 110 on the holders. When a bobbin is finished a spare bobbin is moved from the holder to

the spinning head so that a long length of wire can be covered without having to cut the wire to insert a new bobbin of covering material on the spinner head. The machine 5 shown is for double covering but single covering can be effected by the machine in which case one of the spinners in each pair would not be fed with covering material.

What I claim and desire to secure by Letters Patent is:—

1. In a machine for covering wire, the combination of a series of spinner heads arranged one in advance of the other and disposed on a substantially horizontal axis, flyers 15 on said spinner heads, a separate drive for each spinner head for rotating the same in opposite directions, a winding bobbin for each pair of spinner heads, a series of tubular bobbin holders each arranged in axial 20 alignment with one of said spinner heads for supporting spare bobbins, and mechanical means for varying the relative speed of the flyers and the winding bobbins.

2. In a machine for covering wire, the

combination of a plurality of flyers, a plurality of winding bobbins, means for driving the flyers, means for driving the winding bobbins, an arm shiftable radially of said bobbin winding means, and a removable motion transmitting member carried by said arm for varying the relative speed of the flyers and winding bobbins.

3. In a machine of the class described, the combination of a plurality of fliers, a main driving shaft for driving the flyers, an arm 35 pivotally mounted thereon, a plurality of winding bobbins, a countershaft for driving the winding bobbins, means carried by said arm for transmitting motion from said main shaft to said countershaft, and means for adjusting said arm radially of said countershaft thereby to permit variation of the speed of the countershaft relative to that of the main shaft.

In testimony whereof I have signed my name to this specification.

JOHN NARIZZANO.
